US00D394613S

United States Patent [19]

Kamimura et al.

[11] Patent Number: Des. 394,613

[45] Date of Patent: **May 26, 1998

[54] ATOMIC ABSORPTION SPECTROMETER

[75] Inventors: **Seiji Kamimura**, Kokubunji; **Mitsuru Oonuma**, Tokyo; **Hayato Tobe**, Mito; **Hiromi Yamashita**, Ishioka; **Hisashi Kimoto**, Hitachinaka, all of Japan

[73] Assignee: **Hitachi, Ltd.**, Tokyo, Japan

[**] Term: 14 Years

[21] Appl. No.: 66,452

[22] Filed: Feb. 12, 1997

[30] Foreign Application Priority Data

Aug. 30, 1996 [JP] Japan 8-25643

[51] LOC (6) Cl. 10-04

[52] U.S. Cl. D10/81

[57] CLAIM

The ornamental design for an atomic absorption spectrometer, as shown and described.

DESCRIPTION

FIG. 1 is a perspective front, right side and top view of an atomic absorption spectrometer showing our new design;

FIG. 2 is a front elevatioanl view thereof;

FIG. 3 is a top view thereof;

FIG. 4 is a right side view thereof;

FIG. 5 is a left side view thereof;

FIG. 6 is a rear side view thereof; and,

FIG. 7 is a bottom view thereof;

1 Claim, 6 Drawing Sheets

FIG. 1

FIG. 2

FIG. 3

*FIG. 4**FIG. 5**FIG. 6*

FIG. 7
